SUBTERRANEAN TRANSFORMER VAULT BAFFLE

Morris Greitzer, Los Angeles, and Simon Greitzer,
Inglewood, Calif., assignors to California Maple,
Los Angeles, Calif., a corporation of California

Filed Nov. 14, 1966, Ser. No. 4,635

Term of patent 14 years

(Cl. D23—154)

FIG. 1.

FIG. 2.

FIG. 3.

FIG. 4.

FIG. 1 is a perspective view of a subterranean transformer vault baffle, showing our new design;

FIG. 2 is a bottom perspective view thereof;

FIG. 3 is a cross-section taken on line 3—3 of FIG. 1; and

FIG. 4 is an enlarged cross-section on line 4—4 of FIG. 2.

We claim:

The ornamental design for a subterranean transformer vault baffle, as shown and described.
